UNITED STATES PATENT OFFICE.

LOUIS P. BLAKELY, OF GERMANTOWN, PENNSYLVANIA.

AUTOMOBILE WASH BRUSH.

Application filed September 8, 1923. Serial No. 661,687.

To all whom it may concern:

Be it known that I, LOUIS P. BLAKELY, a citizen of the United States, residing at Germantown, in the county of Philadelphia and State of Pennsylvania, have invented certain new and useful Improvements in an Automobile Wash Brush, of which the following is a specification.

The present invention relates to brushes 10 of the fountain type, and more particularly to a brush for use in cleaning automobiles.

An object of the invention is to provide a brush with a shield to prevent the dripping water from splashing or running over 15 the back thereof and spraying or splashing the person handling the brush, the shield being adapted to collect the dripping water and carry it to the end of the brush at a suitable point of discharge so that the stream 20 of water, mud and the like may be directed upon the ground at a point remote from the handle of the brush.

Another object of the invention is to provide a brush of this character which is 25 made up of a plurality of separate parts including a brush head forming a portion of a hollow body or cylinder and which is separable therefrom for ready renewal of the parts, and a shield which is spaced from 30 the body or cylinder and mounted thereon as a part of the cylinder to condense the structure and occupy small space as well as to admit packing of the device in a relatively small space.

35 A further object of the invention is to provide a brush with a shield and which possesses the above outlined characteristics and at the same time is compact, simply constructed, and is light in weight and easily handled, the structure and arrangement of the parts being such that the brush may be introduced into various small spaces and beneath the parts of an automobile body and chassis.

40 The above and various other objects and advantages of this invention will in part be described in, and in part understood from, the following detailed description of the present preferred embodiment, the same being illustrated in the accompanying drawings, wherein:

Fig. 1 is a side elevation partly in section of a brush constructed according to the present invention.

Fig. 2 is a fragmentary enlarged section 55 taken longitudinally through the brush head and a portion of the handle.

Fig. 3 is a further enlarged transverse section taken through the brush head substantially on the line 3-3 of Fig. 2.

Fig. 4 is an enlarged fragmentary section 60 through the inner end of the handle and its coupling with a source of fluid supply.

Fig. 5 is a side elevation of a slightly 65 modified form of brush.

Fig. 6 is an enlarged longitudinal section taken through the head of the modified form, and

Fig. 7 is an enlarged transverse section 70 taken on the line 7-7 of Fig. 6 through the head of the modified form of brush.

Referring to the drawings, and first to the construction of brush shown in Figs. 1 to 4, inclusive, 10 designates a handle of suitable length which is hollow and which 75 may comprise a pipe externally threaded at opposite ends. The inner end of the handle 10 is provided with a coupling 11 which is flanged upon a feed pipe coupling 12 which may be a hose or other flexible device which 80 permits the handling of the brush.

The brush head comprises a shell 13 which may be curved longitudinally as shown in Figs. 1 and 2, and which is semi-circular in cross section as shown in Fig. 3. 85 This shell carries bunches of bristles 14 which are arranged in suitable rows or otherwise as may be found desirable, in the shell is provided with outlet openings 15 between and about the bunches of bristles 90 14 and which extend radially through the shell relatively to the center of transverse curvature of the shell.

The shell 13 carries a complementary section 16 which overlaps and fits into the 95 inner open side of the shell to complete the cylindrical formation of the body. The sections 13 and 16 are sealed together by interposed packing strips 17 of rubber or other suitable elastic material. From Fig. 100 2 it will be noted that the outer end of the shell 13 is closed at its inner side to form a

2
cap 18, and it will also be noted that the inner section 16 of the cylindrical body, at its outer end, is closed at its outer side to form a cap 19 of a size to fit snugly within 5 the cap 18 and thus unite the outer ends of the sections.

The inner end of the inner section 16 is of tubular form to provide a coupling nipple 20 which overlaps the inner end of the shell 10 13 and which is internally threaded for detachable mounting upon the outer end of the handle 10.

A shield 21 which is longitudinally curved and transversely bent to conform 15 generally to the curvature of the cylindrical body, is fitted in spaced relation about the inner side of the body. This shield 21 has a closed end which is extended and rounded out to conform to the general curvature of 20 the cap 18 and which is provided with an aperture at its axial portion to receive an endwise projecting stud 22 carried by the cap 18. The stud 22 is shouldered as shown in Fig. 2 to space the end of the shield away 25 from the cap 18.

The inner end of the shield 21 is attached to the cylindrical member by a bolt 23 which may be engaged inwardly through the shell 20, the nipple 20 and through the bottom of 30 the shield 21, a thumb nut 24 being threaded upon the bolt 23 to bind against the exterior face of the shield 21. A spacing sleeve 25 may surround the bolt 23 to space the shield 21 from the inner section 16.

35 Referring now to sheet 2 wherein is illustrated in Figs. 5, 6 and 7 the modified form of the invention, the handle 10 detachably carries a nipple 26 on the inner end of an inner shell section 27 which corresponds to 40 the member 16 of the preferred form with the exception that as shown in Fig. 6 the modified form is straight and extends at an angle substantially 30 degrees from the axis of the nipple 26. This inner shell member 45 27 carries the outer shell member 28 which is also straight, and a shield 29 is mounted upon the straight cylindrical head in accordance with the description above set forth in connection with the preferred form.

50 The construction of both forms of the invention is identical, the only differences being that the brush head of the preferred form is curved throughout substantially 90 degrees for gaining access to certain parts 55 of the automobile body and running gear, and the modified form is straight and extends at an angle to the handle sufficient to insure insertion of the brush head into close places about and beneath the chassis, the 60 fuel tank, and other practically inaccessible parts.

The brush heads may be interchanged upon the handle 10 and various other forms of brush head may be resorted to so that a 65 set of the brush heads may be supplied for

mounting on the single handle and for carrying out different cleaning operations upon an automobile or other article or device which is to be cleaned.

Water is supplied under suitable pressure 70 through the pipe or hose 12, through handle 10 and into the cylindrical head, the water being sprayed through the openings 15 to the bristles 14 and to the surfaces being cleaned. This constant supply or flow of 75 water carries off mud and other accumulations which are loosened or dislodged by the bristles 14 and for the most part runs off of the outer end of the brush head which is inclined downwardly. The water and dirt 80 which run over the sides of the head are caught in the shield 21 and kept from splashing in all directions from the brush. The shield directs the water and accumulations along the inner side of the cylindrical head and directs the flow in a single stream from the end of the head so that the stream is projected away from the handle and the operator is therefore protected.

85 By removing the nut 24 the shield 21 may be quickly removed as this single bolt provides the means for coupling together the two shell sections and also the shield 21. The stud 22 on the outer end of the shell forms the means of support for the outer 90 end of the shield and also forms the spacing member for holding the shield away from the shell to provide the trough or water receiving compartment. When the bolt 23 is removed all of the parts may be separated 95 from one another. As the nipples 20 and 26 are of the same construction they may be interchanged, as shown in Figs. 1 and 5, upon the handle 10.

100 It is of course understood that various 105 changes and modifications may be made in the details of construction and design of the above specifically described embodiment of this invention without departing from the spirit thereof, all changes and modifications being restricted only by the scope 110 of the following claims.

What is claimed is:

1. An automobile wash brush comprising 115 a head, means for supplying water to the head, a stud projecting from the outer end of the head, a shield arranged to fit about the inner side of the head and having an opening in its outer end to receive the stud 120 for supporting the outer end of the shield, and releasable means engaging the inner end of the shield for detachably securing the same to the head.

125 2. An automobile wash brush comprising 130 a pair of interfitting semi-cylindrical sections, bunches of bristles mounted in the outer section and said section having openings therein between the bristles, a packing between said sections, said sections having at their outer ends interfitting caps

- adapted to interlock said sections together at one end, and a detachable bolt engaging the inner ends of said sections for detachably binding the sections together.
5. An automobile wash brush comprising a pair of semi-cylindrical shell sections arranged with one section telescoping into the open side of the other section and said sections having closed cap ends adapted to 10 interfit at the outer end of the brush, the inner section having a nipple upon its inner end, a bolt detachably engaging through the inner ends of said sections to bind the same together, the outer cap having an 15 axial stud thereon, a shield spaced about the inner section and having a cap end with an aperture therein for receiving said stud,
- said shield having an opening in its inner end to receive said bolt therethrough, and a spacer mounted on said bolt between the 20 inner section and the shield.
4. An automobile wash brush comprising a hollow handle, an elongated arcuate tubular body secured at one end to one end of said handle, bristles extending from the convexed surface of the tubular body and having discharge openings arranged thereabout, and a shield detachably secured adjacent its end portions in spaced relation about the convexed surface of the tubular 25 body for directing drippings from the tubular body away from the hollow handle.

LOUIS P. BLAKEY.
